UNITED STATES PATENT OFFICE.

EDWIN FORBES, OF FLATBUSH, NEW YORK.

APPARATUS FOR STARTING RACERS.

SPECIFICATION forming part of Letters Patent No. 481,260, dated August 23, 1892.

Application filed December 30, 1891. Serial No. 416,514. (No model.)

To all whom it may concern:

Be it known that I, EDWIN FORBES, of Flat-
5 bush, in the county of Queens and State of
New York, have invented a new and useful Im-
provement in Apparatus for Starting Racers,
of which the following is a specification, refer-
ence being had to the accompanying draw-
ings.

This invention consists in a light fence,
10 gate, or screen suspended from a swinging
carrier, which is so operated and controlled
in part by an automatic lifting device and in
part by the starter that on the horses or other
racers moving slowly toward it side by side
15 it may be kept slowly moving in the same di-
rection by the said lifting device under the
control of the starter until the said racers are
all in perfect alignment and then left under
the control of said lifting device, to be there-
20 by suddenly lifted clear out of the way.

Figure 1 represents a side view of the ap-
paratus, partly in section, showing the fence,
gate, or screen in position to commence bring-
25 ing the racers into alignment. Fig. 2 is a per-
spective view of a portion of the race-course,
showing the apparatus in the position it as-
sumes when liberated after the racers have
been brought into alignment.

Similar letters of reference designate cor-
30 responding parts in all the figures.

A A' are two standards arranged opposite
each other, one on each side of the track of
the race-course at or near the line whence the
start is desired to be made.

35 B C C D designate the swinging carrier, con-
sisting of a horizontal shaft B, two parallel
arms C C, secured on said shaft near the ends
thereof, and a pivot or rod D, secured be-
tween the said arms. The shaft B is fitted
40 to turn in bearings in the upper parts of the
standards A A' at such a height that the
racers may pass freely under the said shaft
when the way between the standards is other-
wise unobstructed.

45 E is the fence, gate, or screen, hereinafter
termed "gate," consisting of a light frame,
upon which is stretched any suitable light
fabric, preferably light wire-netting. This
gate is suspended at its upper edge by loops
50 or hangers a from the rod D of the carrier, so
that it will hang vertically from said rod in

all positions which the carrier may assume in
its swinging movement.

On one end of the shaft B there is secured
a pulley F, over which passes a rope b, to one 55
end of which, depending from one side of the
pulley, is attached the automatic lifting de-
vice, which in the example represented is a
weight G, though it is obvious that a spring
connecting the end of the said rope at a suit- 60
able fixed point might be the equivalent of
the weight. The other part of the rope de-
pending from the other side of the pulley
passes under a guide-pulley c and thence to
a controlling apparatus, as a windlass H, on 65
the starter's stand I, which is some distance
forward of the standards A A'.

A stationary cushion or spring-buffer J is
represented as applied under the weight G to
take up the concussion produced by the fall 70
of the weight. A guide d is represented in
Fig. 1 as applied to guide the weight in its
ascent and descent, and a stop f, which may
consist of a steel spring, is represented in Fig.
2 on the post A to act in combination with a 75
downward or rearward extension of one of the
arms C of the carrier to steady the carrier and
gate when they have been thrown up to the
position shown in Fig. 2.

The operation of this apparatus is as fol- 80
lows: When at rest, the weight is on the cushion
J and the arms of the carrier C are di-
rected upward from the shaft F, as shown in
Fig. 2 and in dotted outline in Fig. 1. At
other times than during the starting of a race 85
the weight G rests upon the cushion J, and
the arms of the carrier are turned upward, as
shown in Fig. 2 and in dotted outline in Fig. 1,
so that the gate hangs suspended above the
shaft, leaving the way clear under the shaft. 90
When the start is to be made, the starter, by
means of the windlass H or controlling device,
winds up or draws in the rope b, raising the
weight G and turning the carrier in the direc-
tion of the arrow 3 until the gate is brought 95
to a position in rear of the standards A A', as
shown in bold outline in Fig. 1. The racers
are then brought up to the gate as nearly as
practicable in alignment with each other.
The starter then slowly lets out the rope b 100
and allows the weight to descend and turn
the carrier in the direction of the arrow 4 un-

til the racers are all brought into exact alignment for starting, when the starter releases the controlling device or windlass H, and the weight G, falling suddenly, continues the 5 movement of the carrier in the direction of the arrow 4, and in an imperceptibly small space of time throws the gate up to the elevated position above the shaft, leaving the way open.

10 It will be understood that this apparatus is applicable to starting horses for either running or trotting races, and, in fact, may be used for starting any racers whatever.

What I claim as my invention, and desire 15 to secure by Letters Patent, is—

1. The combination, in an apparatus for starting races, of a swinging carrier and standards containing bearings therefor, a gate sus-

pended from said carrier, an automatic lifting device applied to said carrier for lifting 20 said gate, and a controlling device applied to said carrier for controlling the operation of the lifting device, substantially as herein set forth.

2. The combination of the posts or stand- 25 ards A, the swinging carrier consisting of the shaft B, arms C C, and pivot D, the gate E, suspended from said pivot, the pulley F on said shaft, the cord or rope b, the weight G, and the windlass H, all substantially as here- 30 in set forth.

EDWIN FORBES.
